(74) Attorney, Agent, or Firm — Banner & Witcoff, Ltd.

(57) **CLAIM**

The ornamental design for a display screen or portion thereof with graphical user interface, as shown and described.

DESCRIPTION

The FIGURE is a front view of a display screen or portion thereof with graphical user interface showing our new design. The broken line showing the floral images, shopping bag icon and portion of the display screen is provided for the purpose of illustrating portions of the article that form no part of the claimed design.
